CIGARETTE TOBACCO FEEDING METHOD
AND MACHINEArthur Podmore, London, England, assignor to
American Machine & Foundry Company, a cor-
poration of New JerseyApplication November 21, 1928, Serial No. 320,871
Renewed August 3, 1932

8 Claims. (Cl. 131—39)

This invention relates to an improved method and apparatus for feeding tobacco to continuous rod cigarette machines. Hitherto, despite a great deal of effort directed toward obtaining uniform cigarettes, substantial differences in the weights and density of the cigarettes produced during one run of a given machine have been common, these differences sometimes amounting to 10% or even more in the weight of the cigarettes.

Generally, in machines of this type, a sheet of tobacco is fed from a mass and the tobacco is disentangled and discharged from this sheet to the rod forming means of the cigarette machine. Part of this variation in cigarette weight and density is due to lack of uniformity in this sheet.

The main purpose of this invention is to obtain greater uniformity in this sheet of tobacco, especially in sheet density. Thus, one object of the invention is to level off excess tobacco from the mass above the filling position of the feeding means to thereby initially suppress inaccuracies of density due to varying weights and thickness of tobacco at this position. Another important object is to provide for correcting plus or minus errors in density of the initially corrected sheet. Another object is to provide means for tamping out voids or air pockets in the layer of tobacco above the filling position of the feeding means while subjecting all parts of this layer to the same pressure.

With these and other objects in view, the invention consists in certain constructions and combinations which will be hereinafter fully described and then set forth in the hereunto appended claims.

In the accompanying drawings which form a part of this specification and in which like characters of reference indicate the same or like parts:

Fig. 1 is a sectional side elevation of a machine illustrating the improved method and apparatus for feeding tobacco;

Fig. 2 is a front elevation, partly broken away, of the machine shown in Fig. 1, seen from the left hand side of Fig. 1;

Figs. 3 and 4 are left and right hand side elevations, partly broken away, of the machine shown in Fig. 1;

Fig. 5 is a plan view of the machine shown in Fig. 1, with the side frames and drives omitted; and

Fig. 6 is a detail side elevation showing operation of the raking and tamping devices.

In carrying the invention into effect, the cigarette tobacco feeding method is employed

wherein a sheet of tobacco is progressively formed from a mass of tobacco, and any excess tobacco near where the sheet is formed is raked back over the mass so as to initially govern the density of the sheet; and wherein plus or minus inaccuracies of sheet density are corrected by subjecting the sheet to the action of an auxiliary supply of tobacco which furnishes additional tobacco to compensate for minus inaccuracies and which is arranged to absorb tobacco from the sheet to compensate for plus inaccuracies; and wherein tobacco is disentangled and discharged from the corrected sheet to furnish a uniform stream of tobacco to the rod forming means of the cigarette machine. In the apparatus selected to carry the invention into effect, there is provided means for progressively forming a sheet of tobacco from a mass, means for periodically raking excess tobacco back over the mass to initially govern the density of the sheet, means for causing an auxiliary supply of tobacco to furnish additional tobacco to said sheet to compensate for minus inaccuracies of sheet density and to absorb tobacco from said sheet to compensate for plus inaccuracies of sheet density, together with means for disentangling and discharging tobacco from the corrected sheet in order to provide a uniform stream of tobacco. Preferably, the sheet forming means will also include tampers coating with said raking means to eliminate air pockets and otherwise govern the initial density of the sheet. In the best constructions also, the sheet forming means will include a feed drum supporting the mass of tobacco. These various steps and parts may be widely varied in construction within the scope of the claims, for the particular machine selected to illustrate the invention is but one of many possible concrete embodiments of the same. The invention, therefore, is not to be restricted to the specific method and apparatus illustrated and described.

Referring to the drawings, the supply of tobacco T in the casing 10 is supported, as shown in Fig. 1, on a relatively large main feed drum 17 provided with the usual card pins, the tobacco supply being retained on the drum by an inclined wall 16 and by the sidewalls of the casing. This retaining wall is pivotally mounted between the sidewalls of the casing with its lower end adjacent the surface of the main feed drum, and is made adjustable so that it can be set at the proper angle to suit the quality and condition of the tobacco used. The casing 10 is suitably supported by frames 11 and 12 connected by a tie rod 15 and supported on pedestals 13 and 14. Above the

feed drum 17, and beyond a vertical plane through its axis, is positioned a filling drum 18 which cooperates with the feed drum to form a sheet of tobacco thereon from the supply of tobacco resting on the feed drum and to brush back surplus tobacco.

For the purpose of compensating any plus or minus inaccuracies in the density of the sheet of tobacco on the drum to fill or brush off respectively areas containing more or less than the proper amount of tobacco, a second filler drum 19 spaced beyond the filler drum 18 along the peripheral surface of the feed drum 17, is provided. This second filler drum maintains an auxiliary supply of tobacco in the angle between it and the feed drum, as shown in Fig. 1. This auxiliary supply will be slowly rotated by the rubbing and rolling action of the feed drum and the filler drum 19, and in case of a plus inaccuracy in the density of the sheet of tobacco on the feed drum, the excess tobacco, which by reason of the spaced relationship of drums 19 and 18 has had opportunity to expand through the springiness of the tobacco, will be rubbed or brushed off and absorbed by the auxiliary supply. On the other hand, if there is a minus inaccuracy in the sheet of tobacco passing out from under the filler drum 18, this auxiliary supply resting and rubbing on the sheet of tobacco will tend to fill in the deficient portion of the sheet to uniform density. Thus, the sheet of tobacco passing out from under the filler drum 19 will be substantially uniform.

In order to press out any air pockets or void spaces which may occur in the mass of tobacco near the filling position at the top of the drum 17 and at the same time maintain uniform pressure on the tobacco resting on the feed drum at this position, particularly across the width of the drum, a row of independently movable weighty tampers 29 are positioned along the width of the drum and are alternately lifted and lowered on to the tobacco to rest thereon by gravity by any suitable means such as those which will presently be described.

The layer of tobacco between the tampers and the feed drum is levelled off and maintained approximately uniform at all times in thickness by means of a series of oscillating rakes 32 mounted on a crank operated shaft 33, to thereby initially control the density of the tobacco sheet by controlling the weight and thickness of the tobacco above the filling position of the drum. Coacting with the oscillating rakes is a series of rotating rakes 34 mounted on a rotating shaft 35.

As shown in Fig. 6, while the tampers 29 are being lifted and after they have reached the position 29' as shown in Fig. 6, the oscillating rakes 32 move from the position near the drum 18 toward the inclined wall 16, thus levelling off and raking back excess tobacco on the tampers and also acting to keep the tampers free from loose tobacco. When the tampers are in lowered position, they rest by their own weight on the tobacco and, consequently, each tamper exerts the same pressure, even though the thickness of the tobacco under the tampers is unequal. The rakes 32 are so spaced that in their operation every other rake element passes through one of the spaces between two successive tampers 29, while the alternate rake elements pass through the slots 86 in the tampers. The rotating rake elements 34 in the position 34'' (Fig. 6), enter between the oscillating rake elements 32 when the latter are in position 32'', thus coacting with said oscillating rakes to receive tobacco there-

from and advance it still farther away from the filling position of the drum 17. The rakes 34 are mounted in pairs, each pair passing through one of the spaces between the tamper mounting bars 30 which are fulcrumed on a shaft 31.

As will be seen from Fig. 1, the combined effect of the main feed drum 17, the filler drum 18, and the rakes 32 and 34 will be to slowly rotate the tobacco supply T resting on the feed drum, in tangential contact therewith.

The driving means for the above described parts are mounted on the side frames 11 and 12. A main drive shaft 36 which is connected with the drive of the cigarette machine or with a separate motor by a chain 37 and a sprocket 38, is provided with a gear 39 in mesh with a gear 40 on a shaft 41. On the other end of shaft 41 is a sprocket 42 which is connected with a sprocket 43 by a chain 44 and this sprocket drives the shaft 45 located in a housing 46. A shaft 47 mounted in the housing is provided with a worm wheel 48 driven by a worm 49 on a shaft 45. Worm 50 on the shaft 47 drives a worm wheel 51 on the feed drum shaft 52 carried by bearings 53 and 54. On the end of the shaft 52 is mounted a sprocket 55 which, by means of a chain 56 running over sprockets 57 on shaft 58 and sprocket 59 on shaft 60, drives the filling drums 18 and 19 on the last two shafts. The drum 20 is driven by a belt 63 which runs over the pulley 64 on the shaft 41 and over a pulley 65 on a shaft 66 in the housing 67. In the housing 67 is a shaft 68 carrying a worm wheel 69 driven by a worm 70 from the shaft 66. A worm 71 on the shaft 68 meshes with a worm wheel 72 on the feed drum shaft 73 in bearings 74 and 75.

The shaft 33 carrying the rakes 32 is mounted in brackets 76 and 77 on angle pieces 78 and 79, and is oscillated by means of a lever 87 connected by a link 88 to a crank 89 on one end of a short shaft 83, the other end of which shaft mounts a crank 82 carrying one end of the crank shaft 81. Also mounted on this shaft 83 is a sprocket 90 connected by a chain 91 to a sprocket 92 on shaft 35 carrying the rotating rakes 34.

The tampers 29 are lifted and lowered by flexible chains 80, the upper links of which ride on the crank shaft 81 supported at one end on crank 82 carried by said shaft 83 mounted in bearing bracket 85, and at the other end on crank 82, the latter crank being mounted on a short shaft 84 in bearing bracket 85'. This shaft 84, which carries a counterweight 112 to balance the weight of shaft 81 and the parts carried thereby, is driven by a sprocket 93 and a chain 94. The chain 94 runs over sprocket 95 on a shaft 96 which also carries a sprocket 97, having on it a chain 98 running over sprockets 99 and 100 supported on shafts 101 and 102 respectively, and over a sprocket 103 on a shaft 104. On the shaft 36 is mounted a sprocket 105 connected by a chain 106 with a sprocket 107 on a shaft 108, which also carries another sprocket 109 operating on the chain 94 by means of a chain 110 running over sprocket 109 and sprocket 111 on shaft 102, the sprocket 111 being fixed with respect to sprocket 100 and thus driving chains 98 and 94 from the main shaft 36.

The tobacco shreds adhering to the filler drums 18 and 19 are removed by conventional wiper rolls 21 and 22 on shafts 113 and 114 mounted in adjustable bearings 115 and 116. The wiper rolls are driven by suitable means, such as motor 117 driving a belt 118 and a pulley 119 on a picker roll shaft 120 in bearings 121 and provided with

a double pulley 122 which connects the pulleys 123 and 124 through belts 125 and 126 respectively.

The uniform sheet of tobacco on the feed drum 17, after emerging from under the filler drum 19, is pressed against the drum by the comb 23 attached to a bar 127 terminating at its ends in studs 128 journaled in the frames 11 and 12. Springs 130 exert tension on levers 129 on the studs 128 and thus yieldingly press the comb against the drum.

As an additional precaution to average up the stream of tobacco from adjacent parts of the sheet formed on the feed drum 17, the tobacco after being picked from the drum 17 by picker roll 25 on the shaft 120, is showered upon the vertical glass wall 27 and thence rebounds on a limited portion of the periphery of the feed drum 20. This layer is held against the feed drum 20 by a comb 24 mounted on studs 132 of a bar 133 and pressed against the drum by springs 135, just prior to being showered by the picker roll 26 on the shaft 136 into the delivery chute 28 which leads to the rod forming mechanism of 25 the cigarette machine.

It is obvious that this second feeding and picking may be dispensed with in the practice of the invention and the tobacco discharged from the drum 17 may be fed directly, or by suitable conveying means to the chute leading to the rod forming mechanism.

The picker roll shaft 136 is mounted in bearings 137 on the frames 11 and 12 and driven directly from the motor 117 by a belt 138 running over pulleys 139 and 140. The delivery chute 28 is supported by screws 141 in the arms of bearings 142 supporting a shaft 143 having knocker means 144 for vibrating the chute. The shaft 143 is driven by a pulley 145, belt 146 and pulley 147.

In view of the foregoing, further description of the operation of the improved method and apparatus for feeding tobacco is deemed unnecessary and is omitted for the sake of brevity.

45. What is claimed is:

1. In a cigarette machine feed, the combination with tampers operating on tobacco, of oscillating rakes and coacting rotary rakes for raking excess tobacco away from said tampers one of 50 said rakes having prongs entering between the tampers.

2. In a cigarette machine feed, the combination with a row of independently movable tampers for operating on tobacco, of means for alternately lifting said tampers and lowering them on to the tobacco to rest thereon by gravity alone to cause the tampers to exert equal pressure along the length of the row while accommodating themselves to unequal thicknesses of tobacco.

60. 3. In a cigarette machine feed, the combination with tampers for operating on tobacco, of means flexibly connected to the tampers for alternately lifting said tampers and lowering them to rest by gravity on the tobacco.

65. 4. In a cigarette machine feed, the combination with tampers for operating on tobacco, of means flexibly connected to the tampers for alternately lifting said tampers and lowering them to rest by gravity on the tobacco, said means comprising a crank shaft above said tampers and flexible members connecting said shaft and said tampers.

70. 5. In a cigarette machine feed, the combination with a rotating carded feed drum, of means for retaining a mass of tobacco on said feed drum,

a rotating carded filling drum above said feed drum and cooperating therewith to form a sheet of tobacco thereon from said mass, a rotating carded compensating drum arranged to maintain an auxiliary supply of tobacco in contact with the sheet formed on the feed drum to compensate plus or minus inaccuracies in the sheet, means operating to remove tobacco from the filling drum and compensating drum and return it respectively to the mass and auxiliary supply, and a picker roll for disentangling and discharging tobacco from the corrected sheet, the compensating drum being substantially spaced from the filling drum, whereby excess tobacco in the sheet may expand while the sheet is carried from the filling drum to the compensating drum and be rubbed or brushed off and absorbed by said auxiliary supply of tobacco.

80. 6. In a cigarette machine feed, the combination with a rotating carded feed drum, of means for retaining a mass of tobacco on said feed drum, a rotating carded filling drum above said feed drum and cooperating therewith to form a sheet of tobacco thereon from said mass, a rotating carded compensating drum arranged to maintain 85

an auxiliary supply of tobacco in contact with the sheet formed on the feed drum to compensate plus or minus inaccuracies in the sheet, means operating to remove tobacco from the filling drum and compensating drum and return it respectively to the mass and auxiliary supply, and a picker roll for disentangling and discharging tobacco from the corrected sheet, the compensating drum being substantially spaced from the filling drum, whereby excess tobacco in the sheet may expand while the sheet is carried from the filling drum to the compensating drum and be rubbed or brushed off and absorbed by said auxiliary supply of tobacco.

90. 7. In a cigarette machine feed, the combination with a rotating carded feed drum, of means for retaining a mass of tobacco on said feed drum, a rotating carded filling drum above said feed drum and cooperating therewith to form a sheet of tobacco thereon from said mass, a rotating carded compensating drum arranged to maintain 95

an auxiliary supply of tobacco in contact with the sheet formed on the feed drum to compensate plus or minus inaccuracies in the sheet, means operating to remove tobacco from the filling drum and compensating drum and return it respectively to the mass and auxiliary supply, and a picker roll for disentangling and discharging tobacco from the corrected sheet, the compensating drum being substantially spaced from the filling drum, whereby excess tobacco in the sheet may expand while the sheet is carried from the filling drum to the compensating drum and be rubbed or brushed off and absorbed by said auxiliary supply of tobacco, spaced slotted tampers resting on the mass of tobacco in front of the filling drum, spaced oscillating rakes entering into said slots and between the tampers for levelling off the layer of tobacco between the tampers and the feed drum and raking back loose tobacco delivered on the tampers by said means.

100. 8. In a cigarette machine feed, the combination with a rotating carded feed drum, of means for retaining a mass of tobacco on said feed drum, a rotating carded filling drum above said feed drum and cooperating therewith to form a sheet of tobacco thereon from said mass, a rotating carded compensating drum arranged to maintain 105

an auxiliary supply of tobacco in contact with the sheet formed on the feed drum to compensate plus or minus inaccuracies in the sheet, means operating to remove tobacco from the filling drum and compensating drum and return it respectively to the mass and auxiliary supply, and a picker roll for disentangling and discharging tobacco from the corrected sheet, the compensating drum being substantially spaced from the filling drum, whereby excess tobacco in the sheet may expand while the sheet is carried from the filling drum to the compensating drum and be rubbed or brushed off and absorbed by said auxiliary supply of tobacco, spaced slotted tampers resting on the mass of tobacco in front of the filling drum, spaced oscillating rakes entering into said slots and between the tampers for levelling off the layer of tobacco between the tampers and the feed drum and raking back loose tobacco delivered on the tampers by said means.

110. 9. In a cigarette machine feed, the combination with a rotating carded feed drum, of means for retaining a mass of tobacco on said feed drum, a rotating carded filling drum above said feed drum and cooperating therewith to form a sheet of tobacco thereon from said mass, a rotating carded compensating drum arranged to maintain 115

an auxiliary supply of tobacco in contact with the sheet formed on the feed drum to compensate plus or minus inaccuracies in the sheet, means operating to remove tobacco from the filling drum and compensating drum and return it respectively to the mass and auxiliary supply, and a picker roll for disentangling and discharging tobacco from the corrected sheet, the compensating drum being substantially spaced from the filling drum, whereby excess tobacco in the sheet may expand while the sheet is carried from the filling drum to the compensating drum and be rubbed or brushed off and absorbed by said auxiliary supply of tobacco, spaced slotted tampers resting on the mass of tobacco in front of the filling drum, spaced oscillating rakes entering into said slots and between the tampers for levelling off the layer of tobacco between the tampers and the feed drum and raking back loose tobacco delivered on the tampers by said means.

120. 10. In a cigarette machine feed, the combination with a rotating carded feed drum, of means for retaining a mass of tobacco on said feed drum, a rotating carded filling drum above said feed drum and cooperating therewith to form a sheet of tobacco thereon from said mass, a rotating carded compensating drum arranged to maintain 125

an auxiliary supply of tobacco in contact with the sheet formed on the feed drum to compensate plus or minus inaccuracies in the sheet, means operating to remove tobacco from the filling drum and compensating drum and return it respectively to the mass and auxiliary supply, and a picker roll for disentangling and discharging tobacco from the corrected sheet, the compensating drum being substantially spaced from the filling drum, whereby excess tobacco in the sheet may expand while the sheet is carried from the filling drum to the compensating drum and be rubbed or brushed off and absorbed by said auxiliary supply of tobacco, spaced slotted tampers resting on the mass of tobacco in front of the filling drum, spaced oscillating rakes entering into said slots and between the tampers for levelling off the layer of tobacco between the tampers and the feed drum and raking back loose tobacco delivered on the tampers by said means, and spaced rotary rakes entering between the tampers and oscillating rakes and receiving the tobacco from the oscillat-
